(57) **CLAIM**

The ornamental design for coupler for a top rail of playpen,
as shown and described.

DESCRIPTION

FIG. 1 is a perspective view of coupler for a top rail of
playpen showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof; and,

FIG. 8 is an environmental perspective view and FIG. 9 is
a reduced scale environmental perspective view with the
broken line showing of environment being for illustrative
purposes only and forming no part of the claimed design.
